BAND BLADE RAZOR

Robert B. Hammons, Clearwater, Fla., assignor to Minnesota-Ohio Oil Corporation, Minneapolis, Minn., a corporation of Minnesota

Filed Aug. 29, 1966, Ser. No. 3,619

Term of patent 14 years

(Cl. D95—3)

FIG. 2 is a left side elevational view.

FIG. 3 is a right side elevational view.

FIG. 4 is a back-face view.

FIG. 5 is a top end view, and

FIG. 6 is a bottom end view.

I claim:

The ornamental design for a band blade razor, as shown.
